Primary Examiner — Lakiya G Rogers*Assistant Examiner* — John A Voytek(74) *Attorney, Agent, or Firm* — Robert N. Lipsik(57) **CLAIM**

The ornamental Design for a tire tread wear indicator, as shown and described.

DESCRIPTION

FIG. 1 is a fragmentary perspective view of a tire tread wear indicator showing our new design;

FIG. 2 is an enlarged fragmentary perspective view from the circled area shown in FIG. 1;

FIG. 3 is an enlarged partial front elevational view from the circled area shown in FIG. 1; and,

FIG. 4 is a cross-sectional view taken along Line 4-4 of FIG. 3.

In the drawings, the broken lines showing of a tire depict environmental subject matter and form no part of the claimed design.
